CHANDELIER

Filed Nov. 27, 1929

UNITED STATES PATENT OFFICE

DAVID SCHAEFER, OF BROOKLYN, NEW YORK

CHANDELIER

Application filed November 27, 1929. Serial No. 410,027.

My invention relates to extensible lighting fixtures, such as chandeliers; more particularly, to electrical fixtures which may be used for intensive or general illumination.

5 It is an object of my invention to provide an electrical fixture in the nature of a chandelier which may be so suspended as to make it readily available for general illumination, as when the room is used for a living room, and 10 extend the same for more intensive illumination, as over a table, when the room is used for a dining room.

It is a further object of my invention to provide an electrical fixture in the nature of a 15 chandelier which is extensible from the point of suspension to a point close to the ceiling or over a table, and which comprises all the intricate casting parts and weight of a highly ornamental chandelier, and at the same time 20 retain the requisite strength for the movable parts thereof in whatever position the chandelier may be disposed, assuring against any danger of displacement or hazard of short 25 circuiting of the electrical conductors necessary for illuminating the incandescent lamps.

Other objects of my invention reside in the provision of an easily adjustable, extensible chandelier, which is highly ornamental and has such construction for the electrical conductors thereof to be free from fire hazard so 30 as to meet the rigid requirements of the fire underwriters in the installation of such types of construction.

To attain these objects and such further 35 objects as may appear herein or be herein-after pointed out, I make reference to the accompanying drawings, forming a part hereof, in which—

40 Figure 1 is a plan view of my device with parts broken away to show details;

Figure 2 is a section taken on the line 2—2 of Figure 1, with the chandelier proper removed;

45 Figure 3 is a section taken on the line 3—3 of Figure 1;

Figure 4 is an enlarged fragmentary, longitudinal, sectional view.

Making reference to the drawings, it will 50 be observed that my device comprises a fixture 10, having a capital or canopy 11, adapted to

be attached to the ceiling of a room, and a chandelier 12 arranged to suspend from the arms 13 and equal number of sockets 14 for electrical incandescent lamps 15. Immediately over the chandelier 12 there is provided 55 a ring 16, attached to the chandelier by clips 17 and to this ring, at the orifices 18, there is affixed a series of chains 19, corresponding in number to the orifices, by means of the hook 20. The chain is passed through the canopy 60 to pass over the guiding rolls 20', suspended in the openings 21 of the canopy by means of the pins 22. The opposite end 23 of the chain, after passing over the guiding roll 20, is affixed to a counterpoise 24 at the ring 25 thereon provided, by means of a hook member. This counterpoise is calculated to be of a weight sufficient to balance the chandelier in the various adjustable positions as the chains 65 roll over the guiding roller 20. 70

The counterpoise weight 24 may be a heavy metal ball of general ornamental appearance but is preferably a hollow shell, which may be filled with lead shot to give the desired counterpoise weight to this member and for purposes of retaining the desired rigidity to this member, as well as for other purposes, as will appear as this description proceeds, there is suspended from the lug 26 of the canopy a 75 tubular guiding member 27. This not only serves as a guide but also as the means for leading the conductors 28 to the chandelier 12, previously described.

The lower end 29 of the tube 27 terminates in the head of a series of telescopic tubes 30, 31, 32 and 33. This end 29 has an enlarged eye 34, to one side of the fitting 35 of the tube 30, and the tube 27 is thereby held in position by a collar 36, through which there is passed the set screw 27, bearing against the tube 27. Disposed from the enlarged eye 34 there is provided a lug 38, to which is attached a nipple 39, from which there is suspended a rod 40. The lower end of the rod 40 passes slidably and telescopically into the tube 41, which is threaded into the neck 42 of the chandelier 12, in the central portion 43 of the spider 44.

With the assembly as provided, the conductor 28 is passed through the orifice to the tube 100

27, out through the enlarged eye 34 and then coiled about the rod 40 and tube 41 and then its lower end 28' is connected with the chandelier and spliced in several directions to the conductors for illuminating the incandescent lamps 15.

In order to take care of the proper length of conductor for the various adjustable positions of the chandelier, it is preferred to dis-
10 pose the chandelier so that it is distended to the fullest length from the ceiling or support, at which time the conductor 28 is coiled about the rods 40 and 41 to give it sufficient length. Upon raising the chandelier, the rod 40 will
15 telescope within the tube 41 and serve as a guide for the coils of the conductor 28, assuring against displacement and preventing any rubbing which may affect the insulation.

For shielding the conductor and its guide, the telescopic tubes 30, 31, 32 and 33 are fixed between the head 35 and the neck 42 by means of a collar 45, which is screw threaded in the neck 42. The telescopic members 30, 31, 32 and 33 each have at one end thereof collars
25 46, 47, 48 of the same diameter as the next preceding tube 30, 31, 32 and 33, respectively, and make snug fit but permit slidable engagement with each successive tube. The lower ends of the tubes are provided with enlarged
30 flanges 49, 50 and 51, of a diameter which will give snug but slidable fit within the tubes 31, 32 and 33, respectively.

After assembly of the rod 40, tube 41 and the insulated conductors 28, in coiled position, the telescopic tubes 30, 31, 32 and 33, which have been previously moved back over the tube 27, are slid down over the assembly of the rod 40, the tube 41 and the coiled conductor so that the last tube 45 may be threaded into the funnel-shaped neck 42. The tubes 33 and 45 may be soldered to each other adjacent the point 50, to finally assemble the parts.

With the construction as described, the chandelier may be extended to and from a support holding the capital or canopy 26, with great facility and ease, the weight 24 serving to counter balance this chandelier in any of its positions. With the chandelier either extended well away from the ceiling or similar support, or contracted, the tubes 40 and 41 will guide the excess length of insulated conductor so that this relatively flexible member will conduct the supply of electrical current necessary for illuminating the lights 15. During this movement, the telescopic tubes 30, 31, 32 and 33 will accommodate themselves to any change in length and this, perhaps, coupled with the guide formed by the rod 40 and the tube 41, will hold the chandelier relatively rigidly, as if it were made out of a single suspending member. In addition, also, as the chain 19 is made of flat, ribbon-like members, it will give additional rigidity to the suspension of the chandelier.

65 Additionally, also, though the chandelier is

extensible and movable relatively to the support, the wires or insulated conductors will not be in any way visible and the excess length necessary for accommodating the parts to this adjustment will be well protected by the 70 telescopic tubular members which shield and encase this part.

Thus, I have provided an electrical fixture which is readily extensible, to serve on the one hand as a chandelier, when used near the 75 ceiling, but which may be extended to give more direct illumination, as when the chandelier is required to be used for illumination over a table. Thus, ordinarily in a living room, where a light would be positioned at a high level for general illumination, with my chandelier formed extensible as described, the general furniture arrangement may be for that of a dining room and obtain the requisite illumination in effecting this change. 80 At the same time I provide an electrical fixture which will satisfy all the rigid requirements of fire underwriters as to being free from hazard in the handling of a live electrical conductor, to thereby prevent any possibility of fire due to short circuiting of the current. This is obtained by the rigid guide for the electrical conductor, combined with the telescopic tubes. All this is accomplished without in any way detracting from 85 the ornamental appearance of the fixture.

Having thus described my invention and illustrated its use, what I claim as new and desire to secure by Letters Patent, is—

1. An extensible lighting fixture of the 100 character described comprising a chandelier, a counterpoise therefor, a guide for said counterpoise, an electrical conductor connecting said chandelier, and including an excess coiled portion, a telescopic connector for said 105 guide and chandelier, and telescopic guiding means for said conductor serving to keep said telescopic member, chandelier and guide in sliding alignment.

2. An extensible lighting fixture of the 110 character described, including a chandelier, means for counter-poising said chandelier in its various extensible positions, a counterpoise guide, an electrical conductor through said guide for said chandelier having an excess length to accommodate the various positions of the chandelier, and aligned connected guiding means for maintaining said chandelier in alignment with said guide, serving as a guide for said excess length of conductor, a telescopic sheath connecting said chandelier and guide and enclosing said aligning means. 115

In witness whereof I have hereunto signed my name this 26th day of November, 1929.

DAVID SCHAEFER. 125
